CLAIM

The ornamental design for an agricultural tractor cabin, as shown and described.

DESCRIPTION

FIG. 1 is a front elevational view of an agricultural tractor cabin showing our new design;

FIG. 2 is a right side elevational view thereof, the left side being a mirror image;

FIG. 3 is a rear elevational view thereof;

FIG. 4 is a top plan view thereof;

FIG. 5 is a bottom plan view thereof; and

FIG. 6 is a right side elevational view thereof, the remaining portion of the tractor is shown in broken lines for illustrative purposes only and forms no part of the claimed design.

FIG. 1

FIG. 2

FIG. 3

FIG. 4

FIG. 5

FIG. 6
